UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

HEEL-ATTACHING MACHINE.

1,122,058.

Specification of Letters Patent. Patented Dec. 22, 1914.

Application filed May 7, 1909. Serial No. 494,569.

To all whom it may concern:

Be it known that I, ARTHUR BATES, a subject of the King of England, residing at Leicester, in the county of Leicester, England, have invented certain Improvements in Heel-Attaching Machines, of which the following description, in connection with the accompanying drawings, is a specification, like reference characters on the drawings indicating like parts in the several figures.

This invention relates to heel nailing machines. The machine shown includes mechanism for subjecting a heel and shoe to pressure and means for driving nails through the parts so held under pressure. It will be apparent that as far as the mechanism for applying pressure to the shoe and heel is concerned it could be employed advantageously in machines not equipped with nail driving means, for example in sole laying machines or sole leveling machines. It will be understood therefore that features of the invention may be embodied in machines for other purposes than attaching heels to shoes.

Heel attaching machines are in common use which include a stationary nail block and a jack which is movable toward and from the nail block, the attaching pressure being applied to the shoe and heel by movement of the jack. Other heel attaching machines are in common use in which the nail block is movable and applies pressure to the shoe and heel by its movement toward the jack. While many features of the present invention may be employed in machines of either of these two types the machine herein shown is provided with a movable nail block for the purpose of applying attaching pressure to the shoe heel.

In the machine herein illustrated a jack is arranged for movement toward the nail block to bring a shoe and heel into preliminary engagement or to measure the work, as it is sometimes termed. After the shoe and heel have been brought into engagement the nail block is automatically moved toward the jack a predetermined distance to subject the shoe and heel to attaching pressure. After the attaching pressure has been applied the nail drivers are automatically actuated to drive the attaching nails. In bringing the shoe and heel into preliminary engagement it is desirable that the preliminary or measuring pressure be of a proper

amount. If it is insufficient the subsequent movement of the nail block may not bring the shoe and heel into sufficiently firm engagement, and if it is excessive it will be obvious that the attaching pressure may become so great as to cause liability of breaking the last in case the shoe is heeled upon the last.

A feature of the present invention consists in means for limiting the preliminary pressure applied to the shoe and heel. In the particular embodiment of the invention shown, the jack is moved manually toward the nail block and the mechanism for imparting movement to the jack is so constructed that the pressure applied to the shoe and heel through the jack can never rise above a certain maximum measured by the tension of a spring included in said mechanism.

A further feature of the invention consists in the provision of a single lever to be manipulated by the operator by means of which the preliminary movement of the jack is controlled and also the automatic movement of the nail block and the nail drivers working therein. According to the arrangement shown, by an initial movement of this member the jack is moved toward the nail block to subject the shoe and heel to a preliminary pressure and by further movement of said member the machine is started to effect the automatic movement of the nail block, for subjecting the shoe and heel to attaching pressure, and the subsequent movement of the nail drivers to drive the attaching nails.

To prevent yielding movement of the jack away from the nail block during the application of the final or attaching pressure to the heel there is provided a device for locking the jack in clamping position which is constructed to be rendered effective when the shoe and heel are brought into engagement in the preliminary pressure applying movement.

In the preferred embodiment of the invention there is provided a fluid pressure mechanism for locking the jack from movement away from the nail block which is arranged to be rendered effective upon the clamping of the work. In accordance with a convenient construction the lever by which the jack is controlled is arranged to control the fluid pressure mechanism, the arrangement being

such that upon an initial movement of said lever the work is clamped between the jack and the nail block and upon a further movement of the lever the fluid pressure mechanism is rendered effective to lock the clamping members from separating movement, and upon still further movement of said lever the machine is started to effect the automatic operations previously mentioned.

10 In the preferred form of the invention hereinafter described, the fluid pressure mechanism for preventing separating movement of the clamping members comprises a pressure chamber having a part arranged for movement to vary the size of the chamber which is associated with the jack and arranged to control its position, a passageway leading from the pressure chamber, a valve for opening and closing the passageway and means for actuating the valve to close the passageway arranged to be thrown into operation by the clamping of the work. Upon the closing of the valve in the passageway the part that is arranged for movement to vary the size of the pressure chamber is locked from movement and the jack being associated with said part is locked from movement away from the nail block so that the work may be compressed or nails driven 30 into the work.

Other features of the invention will be hereinafter described in the specification and pointed out in the claims.

Referring to the drawings, Figure 1 is a side elevation, partly in section, of sufficient of a heel attaching machine to enable the embodiment of the present invention shown as incorporated therein to be understood; Fig. 2 is a view similar to Fig. 1 showing 40 the parts of the machine in a different position, and Fig. 3 is a view in detail of a connection forming part of the machine. Fig. 4 is a view in front elevation with parts in section.

45 The present embodiment of the invention is herein shown applied to a heel attaching machine of the type in which the shoe and heel are sustained in proper relative position above a nail block provided with the usual nail conduits and drivers for the purpose of driving attaching nails into the heel and shoe. The nail block is arranged to be moved upward to force the heel in engagement with its shoe before the attaching nails 55 are driven into the shoe.

In the drawings, 2 designates a head in which is located the nail block which may be provided with the usual nail conduits and drivers 3 and with any suitable means 60 for actuating the nail drivers. A shoe support is arranged above the nail block and for movement toward and from the nail block. Suitable automatic means is also provided for raising the nail block a predetermined distance to apply the final or

attaching pressure to the work and to hold the work under such pressure while the attaching nails are driven into the work. This means for elevating the nail block may be similar to the mechanism employed 70 in the machine shown in United States Letters Patent to Pope 446,885, for raising the jack to apply the final or attaching pressure to the work and, as shown in Fig. 4, comprises a pair of eccentric cams 5 which are oscillated by connections with side rods 11 extending upwardly from the cross-head 13 and sliding at their upper ends in sockets in the frame 10. The upper of the cams 5 is journaled in a vertically movable carriage 15 upon which the head 2 with the nail block is mounted. The cross-head 13 is reciprocated vertically by an eccentric on the forward end of the main shaft and when its upward movement takes place the carriage 85 15 and the nail block are lifted bodily toward the shoe support. The nailing mechanism comprises the drivers 3 carried by the driver block 7, the plunger 17, and the actuating rod 9 connected at its lower end to the cross-head 13. In the present construction the shoe support comprises a jack post 4 which is provided with an upwardly extending sleeve 6 fitted to slide vertically in a cylinder 8 which constitutes part of the frame 10 of the machine. The sleeve 6 and jack post 4 are maintained normally at their upward limit of movement by a spring 9 that is attached at its ends to studs 12 and 14, projecting respectively from the jack post 4 and cylinder 8.

Within the sleeve 6 is arranged another sleeve 16 restrained from vertical movement by a flange 18 which projects transversely from the upper end of said sleeve and is received between a cap piece 20 and the upper surface of the cylinder 8. The cap piece 20 is recessed to receive the flange 18 and may be secured to the end of the cylinder by screws or by other means. The recess in the cap piece 20 is preferably of such size as will enable the sleeve 16 to move laterally so as to permit it to adjust itself into such relationship with the sleeve 6 that the latter will be enabled to slide freely in a vertical direction. The sleeve 6 is adapted to contain a fluid such as oil and is provided with a valve seat 22 at its lower end into which a mushroom valve 24 is formed to fit so as to close the lower end of said sleeve. It will be observed in the construction described that the lower portion of the sleeve 6 constitutes a fluid pressure chamber and that the lower end of the sleeve 16 forms a passageway leading from the chamber, which passageway is controlled by the valve 24.

The valve 24 is secured to the lower end of a valve rod 26 which extends upwardly within the sleeve 16 and through an opening formed in the top of the cap piece 20. 130

The upper end of the valve rod 26 is pivotally connected at 28 to a lever 30 which has one end pivotally mounted upon a bracket 32 secured to the cap piece 20. A lever 34 is 5 pivotally mounted at 35 upon the jack post 4 and its front end constitutes a handle adapted to be grasped by the operator, the other end of the lever 34 being provided with a connection 36 shown separately, in 10 Fig. 3, by means of which and a link 38 the rear end of the lever 34 is connected with the rear end of the lever 30. The upper end of a rod 40 is also connected to the rear end of the lever 34 by means of the connection 36. 15 The connection 36 is constructed to provide for the angular movements of the link 38 and the rod 40 and to this end said connection comprises a cylindrical plug 42, mounted in a bearing in the end of the lever 34, 20 into which the upper end of the rod 40 is secured by threaded engagement. The lower end of the link 38 is secured by threaded engagement in a pin 44 that is mounted to turn in a bearing formed in the plug 42. Sufficient space is left in the socket around the link and rod to permit of their angular movement when the lever 34 is actuated. 25

The link 38 is pivotally connected to the rear end of the lever 30 by a connection 30 which permits the link to yield upwardly independently of said lever. In the construction shown, the link 38 passes through a boss 48 pivotally mounted on the end of the lever 30, and a coil spring 50 arranged 35 about the link with its lower end in engagement with a collar 52 has its upper end in engagement with said boss. The rod 40 carries a catch 54 which is adapted to engage the end of one arm 56 of a bell-crank lever 40 pivoted upon the frame of the machine, the other arm 58 of which is connected by a link 60 with one end of a lever 62 which may control the starting clutch in the manner described in United States Letters Patent to Pope, 446,885, the arrangement being such that when the lever 56 is raised the lever 62 will be moved forwardly out of engagement with the clutch dog so that the machine will be started to render the nail driving mechanism operative. The catch 54 is provided with a spring 64 which tends to hold it in contact with the end of the lever 56. A radius arm 66 pivotally mounted 45 upon the frame of the machine and having its rear end pivotally connected to the lever 40 is adapted to move the catch piece rearwardly in opposition to the spring 64 when the lever 56 is raised to start the machine. After the machine has been started and the catch piece has been moved rearwardly a sufficient extent to free it from engagement with the end of the lever 56 the latter is moved downwardly by a spring 68 so that, 50 through the medium of the link 60, the lever 62 will be moved rearwardly to a position in

the path of the clutch dog and enable it to stop the machine at the completion of one revolution of the driving shaft. Effective connection between the lever 56 and the rod 40 is re-established when the hand lever 34 is 70 returned to its initial position. A float 70 arranged within the sleeve 16 and constructed to surround the valve spindle 26 is adapted to serve as a splash-preventing device and to prevent the ejection of the liquid 75 from the sleeve during the rapid manipulation of the jack post.

In the operation of the machine shown the shoe to be heeled is placed upon the jack 4 and the heel is placed in proper position 80 upon the nail block beneath the jack. The operator then grasps the handle of the lever 34 and turns the lever upon its pivot 36 so as to bring the shoe down upon the heel and place the latter under a certain amount of 85 manual compression. During this movement it will be observed that the jack 4 is lowered in opposition to the spring 9. Owing to the resistance offered by the spring 68 during the downward movement of the 90 jack the connection 36 is restrained from rising and in consequence the lever 30 will remain unoperated and the valve 24 will be kept away from its seat so as to permit free interchange of fluid between the interior of 95 the sleeve 16 and the fluid pressure chamber below the valve. When the downward movement of the jack 4 is retarded by the engagement of the shoe with the heel, the rear end of the lever 34 will be lifted in the 100 further actuation of said lever to effect through the link 38 the actuation of the lever 30 to close the valve 24. Upon the closing of the valve 24 the passageway leading from the fluid pressure chamber is 105 closed so that the jack 4 is locked from upward movement. In the further actuation of the lever 34 the rear end of said lever as it moves upward will, through the agency of the connecting mechanism previously described, cause the lever 62 to move out of the path of the clutch dog so that the machine will be started. Upon the starting of the machine, the nail block is elevated to apply the final pressure to the heel and the attaching nails are driven into the heel by the nail driving mechanism. When the nailing operation has been completed the lever 34 is 110 swung upwardly by the operator and moves first about its fulcrum 35, which is held stationary until the valve 24 has been opened. After the valve has been opened, further movement of the lever takes place about the fulcrum 36, the jack 4 being thereby elevated 115 to its initial position.

The amount of liquid imprisoned in the fluid pressure chamber beneath the valve 24 will vary according to the extent the jack has been lowered, which will depend upon the thickness of the heel operated upon, but 120 125 130

whatever may be the amount of liquid below the valve it will afford a firm abutment for the heel during the application of the heavy final pressure exerted by the machine and the subsequent driving of the nails. The provision of the spring 50 in the connection of the link 38 with the lever 30 permits the necessary lost motion of the link 38 after the valve 24 has been closed and while the starting device is being actuated.

It will be seen in the construction shown that the amount of preliminary pressure which may be applied to the heel and shoe by the actuation of the lever 34 is limited by the tension of the spring 68, so that the application of an excessive preliminary pressure to the work is prevented.

Having described my invention, what I claim as new and desire to secure by Letters Patent of the United States is:—

1. A heel attaching machine, having in combination, a nail block, a shoe support arranged for movement toward and from the nail block, means for moving the shoe support toward the nail block through a distance determined by the thickness of the work to bring a shoe and heel into preliminary engagement constructed to limit the preliminary pressure applied to the shoe and heel, and means for automatically moving the nail block toward the shoe support to subject the shoe and heel to pressure prior to attaching the heel to the shoe.

2. A heel nailing machine, having in combination, a nail block, a shoe support arranged for movement toward the nail block to bring a heel and shoe into preliminary engagement, means for automatically moving the nail block toward the shoe support into a fixed position to subject the shoe and heel to further pressure, and a single device for controlling the preliminary movement of the shoe support and the actuation of the nail block.

3. A heel nailing machine, having in combination, a nail block, a shoe support arranged for movement toward the nail block to bring a heel and shoe into preliminary engagement, means for automatically moving the nail block toward the shoe support into a fixed position to subject the heel and shoe to further pressure, and a device arranged for manipulation by the operator for controlling said preliminary engagement of the heel and shoe and constructed to bring said means into operation subsequent to said movement of the shoe support.

4. A heel nailing machine, having in combination, a nail block arranged to sustain a heel in attaching position, a shoe support arranged for movement toward and from said nail block to press a shoe into engagement with said heel, means for locking the shoe support in a stationary position, and a single device for effecting the movement of

the shoe support and controlling said locking means.

5. A machine of the class described, having in combination, relatively movable clamping members for pressing a heel into engagement with its shoe and a hydraulic lock for preventing movement of one of said members away from the other constructed to be rendered operative by the clamping of the work between said members.

6. A machine of the class described, having in combination, relatively movable clamping members, means manipulated by the operator for moving one of said members toward the other comprising a lever pivoted intermediate its ends upon said member and having one end pivotally sustained and arranged to yield in a direction opposite to the clamping movement of said member, and means controlled by said yielding end for locking said member in clamping position.

7. A heel nailing machine, having in combination, nail driving mechanism, including a nail block, a shoe support arranged for movement toward and from said nail block, means for effecting a relative approaching movement of the shoe support and nail block to exert a preliminary clamping pressure between the heel and shoe, means for locking the shoe support in operative position arranged to be actuated by the application of said preliminary pressure, means for actuating the nail block to exert a final pressure between the heel and shoe, and means for driving attaching nails into the heel while the latter is subjected to said final pressure.

8. A heel nailing machine, having in combination, relatively movable clamping members for pressing together parts of a shoe to be attached together, means for effecting a relative approaching movement of said members to exert a preliminary pressure between said parts, means for locking one of said members from movement away from the other member arranged to be rendered effective upon applying said preliminary pressure, means for moving the other member into a fixed position to apply a final pressure to said parts, and means for driving attaching nails into said parts while subjected to said final pressure.

9. A heel nailing machine, having in combination, relatively movable clamping members for pressing together parts of a shoe to be attached, a lever manipulated by the operator arranged to actuate said members upon its initial movement to apply a preliminary pressure to said parts and means, separate from said preliminary pressure applying means, for moving relatively said members to apply a final pressure to said parts arranged to be thrown into operation by a further movement of said lever.

10. A heel nailing machine, having in combination, relatively movable clamping members, means for preliminarily moving one of said members toward the other to clamp the work, nail driving mechanism for inserting nails into the work while so clamped, a device for locking said preliminarily movable member in operative position, constructed to be effective in different 10 positions to which said member may be moved by said means, and means controlled by the clamping of the work for successively actuating said locking device and for effecting the actuation of said nail driving mechanism.

11. A heel nailing machine, having in combination, relatively movable clamping members, one of said members being arranged for preliminary movement toward the other to clamp the work, a device for locking said preliminarily movable member in different operative positions to which it may be moved to accommodate work of different thicknesses, and a device arranged for 25 manipulation by the operator for successively actuating said member and said locking device.

12. A heel nailing machine, having in combination, relatively movable clamping 30 members, a locking device for preventing movement of one of said members away from the other and means for successively effecting movement of one of said members while the other is stationary to apply a preliminary pressure to the work and for actuating said locking device, said means being arranged to unlock said device to permit separation of said members substantially as described.

13. A heel nailing machine, having in combination, relatively movable clamping members, means for actuating said members to exert a preliminary pressure upon the work, means independent of said first-named means for actuating said members to apply a final pressure to the work and fluid pressure mechanism arranged to lock one of said members against movement while the final pressure is applied to the 50 work.

14. A heel nailing machine, having in combination, relatively movable clamping members, means for actuating one of said members to apply a preliminary pressure to the work, means for actuating said members to apply a final pressure to the work, a fluid pressure chamber having a part arranged for movement to vary the size of the chamber, said part being associated with one of 60 said members and arranged to control its position, a passageway leading from the pressure chamber, a valve for opening and closing said passageway and means for actuating the valve to close the passageway arranged to be thrown into operation by the

application of said preliminary pressure to the work.

15. A machine of the class described, having in combination, a heel support and a shoe support arranged for relative approaching movement to press the heel upon its shoe and a device for locking one of said members from movement away from the other, the operation of which is dependent upon the engagement of the heel and shoe 75 with a predetermined degree of pressure.

16. A heel nailing machine, having in combination, relatively movable clamping members, means for preliminarily moving one of said members toward the other to clamp the work, a device operated by said means for locking said preliminarily movable member in the position to which it has been moved, and mechanism controlled also by said means for moving relatively said members to apply a final pressure to the work.

17. A machine of the class described, having in combination, a heel support and a shoe support arranged for relative movement to press a heel upon a shoe, a device for effecting a preliminary approaching movement of one of said members toward the other, said device being movable in the same general direction and at the same time as the movable member, and a lock controlled by said device for holding said member in the position to which it has been moved.

18. A machine of the class described, having in combination, a heel support and a shoe support arranged for relative movement to press a heel upon a shoe, a device for moving one of said members toward the other to effect a preliminary pressure between said members, a fluid pressure chamber having a part connected with said preliminarily movable member arranged to vary the size of the chamber, a passageway leading from said chamber, and a valve arranged 110 for operation by said device to control said passageway.

19. A heel nailing machine having, in combination, oppositely disposed clamping members one of which is movable relatively 115 to the other into different clamping positions, a locking device constructed and arranged to hold the movable member in any clamping position to which it may be moved against movement away from the other member, and an actuator movable in the same general direction as the clamping member and being constructed and arranged, during its initial movement in one direction, to unlock said locking device and to separate said clamping members during its further movement in the same direction.

20. A heel nailing machine, having in combination, clamping members, one of which is movable into different clamping positions, 130

a locking device acting to lock said movable clamping member in whatever clamping position to which it is moved, and a lever connected with said locking device and with one of said clamping members arranged to unlock said device and thereafter retract said clamping member during its movement in one direction.

21. A heelng machine, having in combination, movable clamping members, a locking device for one of said members, and a lever having two fulcrum points, said lever being connected with said locking device and with one of said members and being arranged to swing about one fulcrum to control said locking device and about the other fulcrum to move relatively said clamping members.

22. A heelng machine, having in combination, relatively movable clamping members, means for moving one of said members to subject parts of a shoe to a gradually increasing manual pressure, and automatic means for moving the other of said members for applying mechanical pressure to said parts when the manual pressure has reached a predetermined degree.

23. A heel nailing machine, having in combination, a nailing die, a jack, means operating to move the jack toward the die through a variable distance determined by the thickness of the work, and means operating after said movement of the jack to move the die toward the jack to compress the work.

24. A heel nailing machine having, in combination, a nailing die, a jack, means operating to move the jack toward the die through a variable distance determined by the thickness of the work and means operating after said movement of the jack to move positively the die toward the jack through a predetermined distance.

25. A heel nailing machine, having, in combination, a nailing die, a jack, means operating to move the jack toward the die until arrested by the engagement of the work and means operating after said movement of the jack to move the die toward the jack to compress the work.

26. A heel nailing machine having, in combination, coöoperating members comprising a nailing die and a jack, and means for adjusting the distance between said members comprising a yielding device for moving one member toward the other, locking mechanism for holding the member so moved in adjusted position, and positive means for moving the other of said members in the opposite direction.

27. A heel nailing machine having, in combination, relatively movable clamping members for pressing together parts of a shoe to be attached, a manually operated lever arranged to control, during its initial

movement, the actuation of said members to apply preliminary pressure to said parts, and means separate from the preliminary pressure applying means for moving relatively said members to apply a final pressure to said parts arranged to be thrown into operation by a further movement of said lever.

28. A heel-attaching machine having, in combination, coöperating clamping members including a jack and a nailing die, mechanism for moving one of said members toward the other to subject the work to a preliminary pressure, mechanism for moving the other of said members to subject the work to a final pressure, and a single controlling device separately connected with said mechanisms and arranged to throw them into operation successively.

29. A heel nailing machine having, in combination, nail driving mechanism, work pressing mechanism including a movable pressing member, power actuating means for said mechanisms, a manually operated lever for moving said pressing member into engagement with the work, and connections between the lever and said power actuating means whereby the lever acts to set the latter in operation, said connections being broken when the lever has been moved and being reestablished when the lever is returned to its initial position.

30. A heel nailing machine having, in combination, a jack mounted to swing about a horizontal axis and also to move bodily in a vertical direction, a nail block disposed in the path of vertical movement of the jack, the jack being so constructed and arranged that it may be swung about its axis and then lowered by hand until the work is engaged between it and the nail block, and locking means operating to hold the jack in its lowered position after it has been so moved by the operator.

31. A machine of the class described having, in combination, tools for operating upon a heel, coöperating work engaging and holding members, a hand lever having two pivots and being arranged for moving one of said members into preliminary engagement with the work, a rod connected to the lever adjacent to one of its pivots, and automatic means for actuating said tools arranged to be set in operation by the rod when the lever moves about its other pivot.

32. A machine of the class described having, in combination, tools for operating upon a heel, coöperating work engaging and holding members, a lever having a pivot at one end and another pivot between its ends, the lever being movable about one of said pivots as a fulcrum to move one of the holding members into preliminary engagement with the work and thereafter being movable about the other pivot as a fulcrum, and

actuating mechanism for the tools arranged to be set in operation by the movement of the lever about said second pivot.

33. A heel nailing machine having, in combination, a nail block and jack relatively movable for pressing together a heel and shoe, a manually operated lever arranged to control, during its initial movement, the movement of the jack to measure the work, 10 a spring for determining the maximum measuring pressure, and power driven means for moving relatively said members to apply a final pressure to the shoe parts arranged to be set in operation by a further movement of the lever.

34. A machine for operating on heels, having, in combination, a reciprocatory tool

carrier, power driven means for imparting a working stroke to the carrier, a work support located in line with the path of the carrier, and a manually operated lever having two separated pivot points and being arranged for preliminary movement about one pivot to move the work and carrier relatively toward each other and then about the other pivot to throw the power driven means into operation.

In testimony whereof I have signed my name to this specification in the presence of two subscribing witnesses.

ARTHUR BATES.
